(57) **CLAIM**

The ornamental design for an enclosure for communications device, as shown and described.

DESCRIPTION

FIG. 1 is a rear perspective view of an enclosure for communications device showing our new design;

FIG. 2 is a front perspective view thereof;

FIG. 3 is a front view thereof;

FIG. 4 is a rear view thereof;

FIG. 5 is a top view thereof;

FIG. 6 is a bottom view thereof;

FIG. 7 is left side view thereof; and,

FIG. 8 is a right side view thereof.

The lines in the Figures which bisect the center of the side surfaces of the component in all views are shade lines and are not boundary lines or surface ornamentation. They may be removed from the drawings without departing from the original disclosure.
